UNITED STATES PATENT OFFICE

SIDNEY L. LONG, OF MINNEAPOLIS, MINNESOTA

LIQUID-VENDING MACHINE

Application filed May 29, 1939. Serial No. 366,934.

This invention aims to provide novel means for dispensing material such as liquids, in predetermined quantities, and although a preferred form has been shown, let it be understood that a mechanic working within the scope of what is claimed may make changes without departing from the spirit of the invention.

In the accompanying drawings which illustrate one form in which my invention may be embodied:

Figure 1 is a vertical section wherein the receptacle is lowered; Figure 2 is a similar view with the receptacle raised and in filling position; Figures 3, 4, and 5, are sections taken, respectively, on the lines 3-3, 4-4, and 5-5 of Figure 2.

The frame of the machine includes a box-like housing 1 divided by a partition 2 into a dispensing compartment 3 and a coin compartment 4, access being had to the dispensing compartment 3 through an opening 14 as shown in Fig. 5. A tank 5 is mounted on the housing 1 and discharges into the dispensing compartment 3 through a spout 6 having guides 7 in which slides the stem 8 of a valve 9 that seats on the upper end of the spout 6, upward movement of the valve being limited by a stop 10.

A receptacle 11 is mounted to move up and down in the dispensing compartment 3, and a container such as a paper cup 12 may be placed in the receptacle. The receptacle 11 is mounted on a carrier including a lever 15 and a radius arm 16 disposed parallel to the lever. The lever 15 and the radius arm 16 are pivoted at 17 to the receptacle 11. The lever 15 raises and lowers the receptacle 11, and the radius arm 16 keeps it vertical. The radius arm 16 is pivoted at 20 to a post 18 in the housing 1, and the lever 15 is fulcrumed at 19 intermediate its ends on the post. The lever 15 has an upward extension 21 on which is mounted a pivot element 22 carrying a dog 23 for swinging movement. A pull spring 24, connected to the lower end of the dog and to the extension 21, keeps the dog in such position that its upper end will cooperate with a rack 25 on the post 18. On that end 50 of the lever 15 which is remote from the re-

ceptacle 11, there is a longitudinal guide 26 on which any desired number of weights 27 can be slidably mounted. The lever 15 is adapted to be held in the inclined position of Figure 1 by a latch 29 fulcrumed at 30 on a post 28 in the housing 1. A pin 31 on the post 28 engages in an arcuate slot 32 in the latch 29 and limits the movement of the latch. As shown in Figs. 3 and 4, the latch or locking device 29 is provided with a lower notch 55 60 and an upper notch 61, the purpose of which will presently appear.

The upper end of a link 33 is pivoted to the latch 29, and the lower end of the link is pivoted to a side bracket on a coin lever 34 fulcrumed at 35 on the post 28, the coin lever having a weight 36 at one end, and a coin receptacle 37 at the other, the numeral 38 marking a coin chute carried by the housing 1 and discharging into the coin receptacle 37. 70 The numeral 39 marks a second latch, fulcrumed at 40 on the post 18 and resting on a stop 41 in such a position that the curved upper end 43 of the latch 39 is in the path of a keeper pin 44 on the side of the lever 15. 75 The latch 39 is resilient at its upper end and is held against the stop 41 by a return spring 42 on the post 18. The latch 39 has a seat 45 adapted to cooperate with the keeper pin 44 on the lever 15. A barrier 46 is located 80 between the stem 8 and the receptacle 11, when the receptacle is lowered. The barrier 46 extends under the receptacle 11 when the receptacle is raised as in Figure 2. The purpose of the barrier 46 is to prevent a person from reaching in through the opening 14, shoving up the stem 8, unseating the valve 9, and causing material to be dispensed without having first deposited the requisite coin or token.

The barrier 46 is hinged at 47 to the housing 1 at a point above the opening 14. A link 48 is pivoted at 50 to one edge of the barrier 46, and an operating member 49, which may be a stiff rod, is pivoted at 51 to the opposite edge of the barrier. The operating member 49 slides through the pivot element 22 on the extension 21 of the lever 15, and has a finger 52 which engages the pivot element 22 under circumstances which will be made 95 100

manifest hereinafter. The inner end of the link 48 is pivoted to the upper arm of a bell crank lever 53 fulcrumed on a standard 54 in the housing 1, the lower arm of the bell crank lever having a side pin 55 that extends under the radius arm 16.

In practical operation, suppose that the parts are arranged as delineated in Figure 1 of the drawings. The operator places a coin 10 in the chute 38, the coin rolling along the chute and acquiring lodgment at length in the coin receptacle 37 on the lever 34. The lever 34 is tilted, by the weight of the coin, into the dash line position of Figure 1, and 15 the coin rolls out of the receptacle 37, into the coin compartment 4. When the lever 34 is tilted as aforesaid, by the weight of the coin, the link 33 swings the latch 29 clear of the lever 15, the movement of the latch 29 and 20 consequently the movement of the lever 34 toward the dash line position of Figure 1, being regulated by the length of the slot 32 in the latch 29, wherewith the pin 31 cooperates, in a manner which will be understood readily 25 when Figure 4 of the drawings is noted.

When the lever 15 has been set free, by the operation of the latch 29, as aforesaid, the right hand end of the lever 15, and the receptacle 11 move upwardly, responsive to the action of the weights 27. At this time, 30 the weights 27 are at the inner end of the guide 26 and, as a result, the receptacle 11 is not slammed up violently against the valve stem 8.

As the left hand end of the lever 15 moves 35 downwardly past the horizontal, the weights 27 slide to the left hand end of the guide 26, thereby making the weights the more effective as a means for pressing the receptacle 11 against the valve stem 8. When the right hand end of the radius arm 16 moves upwardly from the position of Figure 1 toward the position of Figure 2, the radius arm 16 no 40 longer bears on the pin 55 of the bell crank lever 53, and the barrier 46 swings by gravity 45 into a vertical position, the operating member 49 sliding longitudinally through the pivot element 22 on the extension 21 of the lever 15. The reason for permitting the barrier 46 to assume a vertical depending position 50 for a time, is in order that the receptacle 11 may be raised from the position of Figure 1 to the position of Figure 2, without hitting the barrier; but by the time that the receptacle 11 is raised to the position of Figure 2, 55 the finger 52 on the operating member 49 has engaged the pivot element 22, and the barrier 46 is swung beneath the elevated receptacle 11.

When the valve stem 8 is raised, and the 60 valve 9 unseated, by the lifting of the receptacle 11, as indicated in Figure 5, the upper end of the stem 8 comes into contact with the stop 10. Liquid flows from the tank 5 through the spout 6 into the cup 12 within

the receptacle 11 and the weight of liquid dispensed is governed by the mass of the weights 27 on the guide 26, since the receptacle 11 will start to move downwardly as soon as the weight of liquid in the cup 12 overcomes the action of the weights 27 plus the friction of moving parts of the mechanism. The receptacle 11 ultimately arrives in the position shown in Figure 1, and the operator can remove the cup 12 through the opening 14. At a predetermined time in the tilting of the lever 15 to the position of Figure 1, the weights 27 slide again to the right hand end of the guide 26. As soon as the left hand end of the lever 15 has been raised far enough, 75 the latch 29 will swing by gravity beneath it, and hold the parts in the position of Figure 1 until another coin is deposited in the chute 38. When the parts are in the position of Figure 1, the radius arm 16 engages the pin 55 and tilts the lever 53, the link 48 swinging the barrier 46 above the receptacle 11, thereby to prevent access to the stem 8, and to avoid the obtaining of material without depositing a coin. 90

When the lever 15 swings from the position of Figure 1 to the position of Figure 2, the keeper pin 44 on the lever 15 engages automatically with the seat 45 in the latch 39, and when the lever 15 swings from the position of Figure 2 to the position of Figure 1, the keeper pin 44 is disengaged from the seat 45 of the latch 39. The latch 39 is employed for two purposes, to wit, to overcome the downward thrust of the valve stem 8, when the receptacle 11 is raised, as in Figure 5, and to overcome the pull of the barrier 46. If there were no valve stem 48, or no barrier 46, latch 39 and the keeper 44 could be dispensed with, since the weights 27 and the liquid in the receptacle 11 serve to tilt the lever 15 back and forth and operate the machine. 100

It will be also noted that the action of closing the barrier serves to check the speed of the receptacle at both the upper and lower position. As the receptacle moves upwardly, the element 22 engages the finger 52 and retards the upward movement of the receptacle. Also, as the receptacle moves downwardly, the arm 16 and the pin 55 operate in a like manner to bring the receptacle gently to rest at the bottom. 110

The functions of the dog and rack previously mentioned are to make a full movement of the mechanism imperative, the main object being to cause the cup to be completely lowered and locked in position before the dog is freed from the rack. Otherwise, a cup could be stopped before it reached the bottom position and before the lever was locked, the liquid taken out, a new cup put in, and sent up to be filled, without the use of a coin. 120

It is to be noted that the action of closing the barrier 46 serves to check the speed of 130

the receptacle 11 at both the upper and lower positions thereof. As this receptacle moves upwardly, the finger 52 engages the element 22 and retards the upward movement of the receptacle. Also as the receptacle moves downwardly, the arm 16 by engaging with the pin 55 operates in a like manner to bring the receptacle gently to rest at the bottom. It is to be noted also that the sliding weight 27 and also the engagement of the dog 23 with the rack 25 serves to vary the speed of the receptacle 11. The function of the dog 23 and the rack 25 is to make a full movement of the mechanism imperative, the main object being to cause the cup to be lowered with the lever ready to be locked in position before the dog is freed from the rack. Otherwise, a cup could be stopped before it reached the bottom position and before the lever was locked, the liquid taken out, a new cup put in, and returned to upward filling position without the deposit of a coin. Two notches 60 and 61 on the latch 29 are used in locking the device as will appear from Figs. 3 and 4. The lower notch engages the lever before the dog leaves the rack while the second notch makes engagement with the lever after the dog 23 leaves the rack 25. If it were not for the lower notch 60, a person might stop the downward movement of the cup as soon as the dog leaves the rack and before the upper notch engages the lever so that the machine might be defrauded in the manner previously stated by a person emptying the cup and refilling it without depositing a coin. While I have disclosed my dispensing machine as being set in operation by a coin, I do not herein claim any novelty in the coin-control mechanism per se, and it is obvious that the machine may be set in operation by other forms of applied force beside the weight of a coin.

Having thus described the invention, what is claimed is:—

1. A dispensing mechanism comprising a lever, means for fulcruming the lever intermediate its ends, a weight, means for mounting the weight on one end of the lever for sliding movement toward and away from the fulcrum of the lever, a receptacle mounted on the opposite end of the lever, a supply valve discharging into the receptacle, the supply valve being opened when the receptacle is raised, the weight constituting means for tilting the lever in one direction, raising the empty receptacle, and opening the supply valve, the weight of the liquid in the receptacle serving to tilt the lever in an opposite direction and lower the receptacle, and means for holding the receptacle releasably in lowered position.

2. A dispensing mechanism comprising a lever, means for fulcruming the lever intermediate its ends, a weight mounted to slide by gravity on one end of the lever, a receptacle mounted on the opposite end of the

lever, a supply valve discharging into the receptacle, the supply valve being opened when the receptacle is raised, the weight constituting means for tilting the lever in one direction, raising the empty receptacle, and opening the supply valve, the weight of the liquid in the receptacle serving to tilt the lever in an opposite direction and lower the receptacle, and means for holding the receptacle releasably in lowered position.

3. A dispensing mechanism comprising as cooperating parts, a lever and a radius arm disposed in approximate parallelism; means for fulcruming the lever intermediate its ends, means for pivotally mounting the radius arm, a weight mounted on one end of the lever, a receptacle mounted on the opposite end of the lever, means for pivotally connecting the radius arm with the receptacle, a supply valve discharging into the receptacle, the supply valve being opened when the receptacle is raised, the weight constituting means for tilting the lever in one direction, raising the empty receptacle, and opening the supply valve, the weight of the liquid in the receptacle serving to tilt the lever in an opposite direction and lower the receptacle, means for holding the receptacle releasable in lowered position, a barrier, means for mounting the barrier movably, and mechanism actuated by one of said cooperating parts for moving the barrier into a position to guard the valve when the receptacle is lowered.

4. A dispensing mechanism comprising a lever, means for fulcruming the lever intermediate its ends, a weight mounted on one end of the lever, a receptacle mounted on the opposite end of the lever, a supply valve operated by thrust and engageable with the receptacle to discharge into the receptacle when the receptacle is raised, the weight constituting means for tilting the lever in one direction and raising the receptacle, the weight of the liquid in the receptacle serving to tilt the lever in an opposite direction and lower the receptacle, means for holding the receptacle releasably in lowered position, and a latch having automatically-releasable engagement with the lever whilst the receptacle is in engagement with the valve, thereby to offset the thrust of the valve.

5. A dispensing mechanism comprising a lever, means for fulcruming the lever intermediate its ends, a weight mounted on one end of the lever, a receptacle mounted on the opposite end of the lever, a supply valve discharging into the receptacle, the supply valve being opened when the receptacle is raised, the weight constituting means for tilting the lever in one direction, raising the empty receptacle, and opening the supply valve, the weight of the liquid in the receptacle serving to tilt the lever in an opposite direction and lower the receptacle, means for holding the receptacle

- receptacle releasably in lowered position, a barrier, means for mounting the barrier for swinging movement, means for connecting the barrier operatively with the lever whereby the lever will swing the barrier into guarding position with respect to the valve, and a latch having automatically-releasable engagement with the lever whilst the barrier is in guarding position with respect to the valve, thereby to offset the drag of the barrier on the lever. 5 70
6. A dispensing mechanism comprising a lever, means for fulcruming the lever intermediate its ends, a weight mounted on one end of the lever, a receptacle mounted on one end of the lever, a supply valve discharging into the receptacle, the valve being opened when the receptacle is raised, the weight constituting means for tilting the lever in one direction, raising the empty receptacle, and opening the supply valve, the weight of the liquid in the receptacle serving to tilt the lever in an opposite direction and lower the receptacle, means for holding the receptacle 15 75
- releasably in lowered position, a fixedly-supported rack, and a dog pivotally mounted on the lever and cooperating with the rack, the throw of the lever being sufficient to carry the dog clear of each end of the rack, the 20 80
- length of the dog being such that it will cooperate with the rack and stop the movement of the lever when an effort is made to reverse the direction of swinging movement of the lever whilst the dog is at a point intermediate 25 85
- the ends of the rack. 30 90
7. In a liquid vending machine, means for holding the mechanism under stress, means for releasing the stress, causing a receptacle to rise and come in contact with a valve, 35 95
- thereby releasing liquid through said valve, means by the weight of the liquid of returning said receptacle to its original position, locking the mechanism again under stress and holding it releasably and a weight shiftable 40 100
- 45 105
- by gravity tending to counterbalance said receptacle. 110
8. In a liquid vending machine, means for holding the mechanism under stress, means for releasing the stress, causing a receptacle to rise and come in contact with a valve, thereby releasing liquid through said valve, means by the weight of the liquid of returning said receptacle to its original position, locking the mechanism again under stress, 50 115
- 55 120
- and holding it releasably, means for guarding the valve while the mechanism is in operation, and means for guarding the valve when the mechanism is at rest. 125
9. A liquid vending machine, comprising 60 130
- a lever, means for fulcruming the lever intermediate its ends, a weight mounted on one end of the lever, a receptacle mounted on the opposite end of the lever, means for holding the lever under stress of weights, means for 65 135
- releasing said stress, thereby causing the receptacle to rise and open a valve releasing liquid into the receptacle, the weight of the liquid causing the receptacle to fall into its original position, and again lock the lever under the stress of the weights, and means for guarding the valve while the machine is in operation and also while it is at rest. 70
10. In a liquid vending machine, means for actuating the mechanism by the weight of the liquid dispensed in combination with slidably mounted weights, and means for varying the speed of said mechanism at different periods of its movements. 75
11. A dispensing mechanism comprising a container for holding the material to be dispensed, a movable member for receiving material dispensed from said container, and a shiftable weight which causes said receiving member when empty to move upwardly to a position adjacent said container, said shiftable weight having a greater counterbalancing action on said receiving member when the latter is in upward position than when in lowered position. 80
12. A dispensing mechanism comprising a container for holding the material to be dispensed, a lever, means for fulcruming said lever, a weight, means for mounting said weight on said lever for sliding movement toward and away from the fulcrum of said lever according to the position of the lever, a receiving member carried by said lever, a control device normally preventing discharge of material from said container and adapted to be moved into releasing condition by upward movement of said lever, and means for holding said lever releasably in lowered position. 90
13. A dispensing mechanism comprising a container for holding the material to be dispensed, a movable member for receiving material dispensed from said container, means for mounting said receiving member whereby it is lowered by the weight of material received thereby, means for lifting said receiving member when emptied, and means for varying the speed of said mechanism at different periods of its movements. 100
14. A dispensing mechanism comprising a container for holding the material to be dispensed, a lever, a member carried by said lever for receiving material dispensed from said container, means for mounting said lever whereby it is lowered by the weight of material received by said member, means for lifting said member when emptied, a rack, and a tensioned dog carried by said lever which engages said rack during the greater portion of movement of said lever in both directions and which releases from said rack when said lever is in upper and in lower position. 110
15. A dispensing mechanism comprising a container for holding the material to be dispensed, a lever, a member carried by said 120
- 125
- 130

lever for receiving material dispensed from said container, means for mounting said lever whereby it is lowered by the weight of material received by said member, and a pivoted latch having two engaging members, one of which engages said lever as it is approaching its lowered position and the other of which engages said lever as it reaches its lowered position.

16. A dispensing mechanism comprising a container for holding the material to be dispensed, a lever, a member carried by said lever for receiving material dispensed from said container, means for mounting said lever whereby it is lowered by the weight of material received by said member, means for lifting said member when emptied in its lowered position, a rack, a tensioned dog carried by said lever which engages said rack during the greater portion of movement of said lever in both directions and which releases from said rack when said lever is in upper and in lower position, and a pivoted latch having two engaging members, one of which engages said lever during its downward movement while said dog is still in engagement with said rack and the other of which engages said lever after said dog is released from said rack.

17. A dispensing mechanism comprising a reciprocating device for carrying the material to be dispensed, means for locking said device under stress, means for unlocking said device by applied force, means for performing the first half cycle of the operation by weights, and means for completing the cycle and locking the device by the weight of the material dispensed.

18. A dispensing mechanism comprising a container for holding the material to be dispensed, a lever, weights associated with said lever, a member carried by said lever for receiving material dispensed from said container, means for locking said lever in lowered position under stress of said weights, means for unlocking said lever by applied force whereby said receiving member is raised into filling position, said lever being lowered by the weight of material dispensed into said receiving member, and positive means for preventing the movement of said lever from being reversed before it has been locked under said stress.

19. A dispensing mechanism comprising a container for holding the material to be dispensed, a lever, a receiving member carried by said lever, a control member normally preventing discharge of material from said container and adapted to be moved into releasing condition by upward movement of said lever, a barrier, and connections between said lever and barrier for moving the barrier beneath said receiving member when the latter is in raised position.

20. A dispensing mechanism comprising a

container for holding the material to be dispensed, a lever, a control member normally preventing discharge of material from said container and adapted to be moved into releasing condition by upward movement of said lever, a barrier, and connections between said lever and barrier for moving the barrier into a position between said control member and said receiving member when the latter is in lowered position.

21. A dispensing mechanism comprising a container for holding the material to be dispensed, a reciprocating member, a receptacle carried by said reciprocating member, a control device normally preventing discharge of material from said container and adapted to be moved into releasing condition by upward movement of said reciprocating member, a counter-balancing device associated with said reciprocating member for causing upward movement thereof when said receptacle is empty, the mechanism being so constructed that a predetermined weight of material in said receptacle serves to move said reciprocating member downwardly, and an automatically releasable device which holds said reciprocating member in upward position whereby the tendency of said control device to close is offset until said receptacle is filled with the predetermined weight of material.

In testimony that I claim the foregoing as my own, I have hereto affixed my signature.
